UNITED STATES PATENT OFFICE.

GEORGE BERNHARDT, OF RADCLIFFE, GREAT BRITAIN.

IMPROVEMENT IN MECHANISMS FOR DOFFING AND APPLYING BOBBINS IN SPINNING-MACHINES.

Specification forming part of Letters Patent No. 123,222, dated January 30, 1872.

SPECIFICATION.

I, GEORGE BERNHARDT, of Radcliffe, in the county of Lancaster, in the Kingdom of Great Britain and Ireland, have invented Improvements in Spinning-Machines, of which the following is a specification:

My invention relates to mechanism for simultaneously removing full bobbins from spinning-machines and replacing them with empty bobbins; and consists in improved modifications, arrangements, and devices hereinafter described.

In the accompanying two sheets of drawing, marked B, Figure 1 is a cross-sectional elevation of so much of a spinning-machine as will be necessary for explaining my invention. Fig. 2 is a front view of the same, showing only one spindle. Fig. 3 is a detached plan of the empty bobbin-rail. Fig. 4 is a detached view in section, showing an alternative arrangement of the empty bobbin-rails; and Fig. 5 is a full-sized detached section of a traveler-ring.

The improvements are illustrated as applied to a ring and traveler spinning-frame. A, the two end frames; A¹, spindle-foot step-rails; A², upper spindle-bearing rails; A³, roller-beams; a, draft or other rollers; b, tin drum or roller for driving the spindles C. The above-named are all ordinary parts of spinning-machines. e, shafts for actuating the coppering or ring rails d. These shafts have wheels e³, clutches e⁴, clutch-forks e⁵, and a shaft, e⁶, to connect the two clutches, as a means of connecting and disconnecting the two shafts e with any ordinary coppering-motion. The wheels e⁷, e⁸, and e⁹ (the pitch-lines of which are shown in Fig. 1) gear the two shafts e together, and also with the wheel f¹ in the boss of the hand-wheel f, loose on the end of the tin-drum shaft. The mechanism is the same upon both sides of the frame, and I shall refer in my description, to make it more clear, to the parts only of one side of the frame. There are wheels e³ on the shaft e, and each of these gears with a rack-bar, e², sliding vertically in bearings in the spindle-rails, the number of these rack-bars depending upon the length of the frame. To the upper end of the rack-bars the ring-rail d is jointed on centers d¹, so that when spinning it may remain in a horizontal position, as shown on the left side of Fig. 1, but may be lifted to

the inclined position shown on the right side of Fig. 1. To one or more of the rack-bars a bent spring, d², is secured, which carries a wedge, d³, which the force of the spring presses against the edge of the ring-rail when horizontal, and, the end of the wedge and the edge of the ring-rail being slightly beveled, the force of the spring tends to hold the ring-rail down in its horizontal position; but when the ring-rail d is lifted the wedge passes between its under side and the top of the rack-bar e² and holds it in the inclined position. This lifting of the ring-rail into the inclined position is accomplished by one or more pins, d⁴, in the ring-rail, which pin comes against the top of the upper spindle-rail A² when the ring-rail is lowered sufficiently. The wedge d³ is withdrawn by causing the incline upon the end of the spring d² to come against an incline-stop, d⁵, secured to the roller-beam A³, by raising the ring-rail sufficiently high. Both these extreme movements of the ring-rail are beyond its ordinary reciprocations when spinning. The rail K for the empty bobbin extends from end to end of the frame, and has diagonal slots K¹ in it, by which it can be secured by screws K² to the framing so as to be moved to and fro by the handle K³ diagonally. The rails on both sides of the frame may be connected by a cross-shaft and two arms, the ends of which fit cross-slots in the rails, so that both may be simultaneously acted upon by moving the cross-shaft if required. In each rail there are as many holes as there are spindles, and these holes, when the machine is spinning, (as shown on the left of Fig. 1,) are midway between the spindles, so that the empty bobbins come in the space between the threads; but when doffing, the rail is slid forward diagonally by pushing endwise at the handle K³ of the rail, and the empty bobbins are thus brought over the centers of the spindles. The wirecurls l¹ are placed in boards l² hinged separately to the empty bobbin-rail, and thus one-half the hole for each empty bobbin is cut out of the sides of each two adjoining wire-curl boards. In the modification shown by Figs. 1, 2, and 3 there is a bottom, K⁴, hinged to the empty bobbin-rail, upon which the bobbins rest, this hinged bottom being partly cut away where it will come opposite each spindle, as shown in Fig. 3. The

hinged bottom is held up, as shown on the left side of Fig. 1, by a tail part, K^5 , from it, which comes under the end of a bent or beveled spring, K^6 , secured to the roller-beam. This spring gives way when the tail part descends, and then escapes past and comes above and holds down the tail part. When the empty bobbin-rail is slid endwise the tail part K^5 is withdrawn from the spring K^6 , which allows the bottom K^4 to fall just when the axes of the empty bobbins come over the spindles. The hinged bottom K^4 is lifted when the empty bobbin-rail is moved back by one arm of a two-armed part, K^7 , centered on a bracket, K^8 , secured to the roller-beam that comes against the under side of the hinged bottom, and the bottom is lifted quite close when the edge of the empty bobbin-rail strikes the other arm of the part K^7 , (see left of Fig. 1,) by which time the spring K^6 will have risen above the tail part. K^X is a pin in the bracket to keep the arms in the part K^7 from falling too far when the bobbin-rail moves forward. In place of the hinged bottom a more simple arrangement may be used formed by a bottom, K^9 , extending from end to end of the frame and fixed to a vertical plate secured to the frame. (See Fig. 4) This fixed bottom sustains the empty bobbins with sufficient accuracy, and their edges are only released from the edge of the fixed bottom a short space before the axes of the bobbins come over the spindles. The lower heads of the bobbins used are notched, and have a groove round them, as shown, and the collar of the brad C^1 upon each spindle is roughly milled, so as to prevent the thread from uncoiling when the full bobbins are lifted from the spindles, and break the thread between the full bobbins and the brads with certainty. The rings upon which the traveler works are each made with an internal projection, n , as shown by the full-size detached view, Fig. 5. This is to prevent the threads from escaping from the traveler when doffing, as they are liable to do when the thread is slackened.

I will now describe the mode of doffing. When the bobbins are full the clutches e^4 are disconnected; then the ring-rails are lowered by the hand-wheel f until they come against a stop, m , which is a sliding pin connected with a spring-handle, m^1 . At this stop a portion of thread is wound in spinning round the boss part of each brad C^1 , and then the machine

is stopped. The stop m is then withdrawn and the ring-rails are lowered by the hand-wheel f until the stop or stops d^4 come against the upper spindle-rail A^2 . This places the ring-rails in the position shown on the right of Fig. 1, so that as they ascend by turning back the hand-wheel f the edge of each ring will come under the end of the full bobbin, which is slid up the spindle, the wire curl l^1 lifting out of the way to allow it to pass and fall from the spindle into any suitable receptacle placed to receive it. The ring-rail d is made to ascend a little after the bobbins have fallen to bring the inclined end of the spring d^2 against the incline-stop d^3 , secured to the roller-beam, and this causes the wedge d^3 to be withdrawn, leaving the ring-rail to fall by gravity and assume its horizontal position. The ring-rail is then lowered and the clutches e^4 brought again into gear. The empty bobbin-rails K are slid forward diagonally, and the empty bobbins X fall upon the spindles, and this completes the doffing operation.

Slack thread is given before the ring-rail is moved upward in doffing by turning forward the draft-rollers to the extent of about one-third of a revolution of the front rollers. The ring-rail may be made to slide forward instead of being hinged, as described; but I prefer to hinge the ring-rail, as shown in Figs. 1 and 2.

Claims.

1. The ring-rail, hinged to the sliding rail or frame, in combination with the devices described or their equivalents, whereby the rings are caused to strike and lift the bobbins, as set forth.

2. The combination of the hinged rail and the pins d^4 , arranged to strike the rail A^2 and tilt the ring-rail, as and for the purpose specified.

3. The combination of the tilting ring-rail, the springs d^2 and wedges d^3 , and the inclined stop d^5 , for the purpose specified.

4. The combination of the sliding bobbin-rail K and the hinged plate K^4 , as and for the purpose described.

In testimony whereof I have signed my name to this specification in the presence of two subscribing witnesses.

GEO. BERNHARDT.
